UNITED STATES PATENT OFFICE.

SAMUEL Y. BUCKMAN, OF PHILADELPHIA, PENNSYLVANIA.

EDGING-MACHINE.

SPECIFICATION forming part of Letters Patent No. 451,265, dated April 28, 1891.

Application filed October 24, 1890. Serial No. 369,160. (No model.)

To all whom it may concern:

Be it known that I, SAMUEL Y. BUCKMAN, a citizen of the United States, residing in the city and county of Philadelphia, State of Pennsylvania, have invented a new and useful Improvement in Machines for Edging Sheet-Metal Plates, which improvement is fully set forth in the following specification and accompanying drawings.

10 My invention consists of an edging-machine for jointing or uniting the adjacent ends of two or more plates of sheet metal, so as to form a continuous sheet of the same, constructed as hereinafter described.

15 Figure 1 represents a plan view, partly broken away, of an edging-machine embodying my invention. Fig. 2 represents a vertical sectional view on line xx , Fig. 1. Figs. 3 and 4 represent, respectively, side views of the 20 ends of two connected plates before and after pressing the same.

Similar letters of reference indicate corresponding parts in the several figures.

Referring to the drawings, A designates a 25 frame or support, in the side walls of which are journaled the rotary shafts B and C.

D and E designate a former or folder and clamp, respectively, operating in the inclined guide or way F, which is secured to the frame.

30 The upper end of the clamp E is formed with a level surface, so as to be adapted to contact with a plate of sheet metal and hold the same firmly against the under side of a bed-plate G while the front edge of the sheet-metal

35 plate is being bent over the edge and on the face of the said bed-plate G by its contact with the upper end of the former D. The lower ends of the former D and clamp E are connected with the toggle-levers J and K, respectively, and the said levers also are pivoted to the frame A and connected to other toggle-levers L and M, also pivoted to the 40 frame.

On the shaft B are the cams N and P, 45 adapted to bear against the levers L and M, respectively, so as to move the same and thereby the levers J and K, and consequently the former D and clamp E.

Q and R designate, respectively, a second 50 former or folder and a second clamp designed

to bend one end of a second plate, so that said end is adapted to engage with the end of the first plate bent by the former D. The former Q is provided with an angular upper end adapted to bear against the plate and 55 press the same against a bed-plate S, fastened to the frame, said bed-plate having a recessed portion S', in which the bent end of the sheet-metal plate is formed.

The parts Q and R are adapted to move 60 freely upon each other in guides T, which are secured to the frame A, similar to the guide F, and have their lower ends connected to the toggle-levers U and V, respectively, which are pivoted to the frame and connected with other 65 toggle-levers W and X, also pivoted to the frame. On the shaft C are the cams Y and Z for operating the said levers W and X, and thereby the levers U and V and the former Q and clamp R.

70 The shafts B and C are provided with bevel gear-wheels A', meshing with the bevel gear-wheels B', loose on the secondary driving-shafts C' and D', and provided with pinion-hubs E', meshing with the mutilated wheels 75 F' on a main driving-shaft G', the latter being parallel with the secondary shafts.

H' and J' designate feed-rollers suitably supported on opposite sides of the edging device for carrying the plates of metal which 80 are to be united to the proper positions for bending the ends thereof.

To operate the secondary shafts C' and D', either together or separately, the following-described mechanism is employed: On the 85 main shaft G' are the gear-wheels K', meshing with the gear-wheels L' L', loosely mounted on the said secondary shafts.

M' and N' designate counter-shafts having suitable bearings and operated by bevel-wheels P' Q' thereon, which mesh with the bevel-wheels R' S', secured to the main shaft. On the shafts M' N' are the cam-grooved wheels or drums T' U', respectively, in the cam-grooves of which are inserted the ends of the 95 pivoted levers V' W', so that the said levers are moved by the rotation of said drums. The other ends of the said levers are connected to the clutches X' Y', which are so secured to the shafts C' D' that when connected 100

to the loose wheels L' L' the rotation of the main shaft will rotate the said secondary shafts. The grooved ways in the drums T' U' are so formed that the clutch X' of the 5 shaft C' is connected with its wheel L' a little in advance of the connection of the clutch Y' with its loose wheel L', so that the sheet-metal plate which has received the bend in its front end can be advanced in time to engage the plate that has received a bend on its rear end.

The operation of the device is as follows: The main shaft G' being set in motion, the feed-rollers H' J' are operated by means of 15 the secondary shafts and connecting mechanism, so that a plate of sheet metal fed to the roller H' is advanced until its front end is in the proper position or projecting a little beyond the edge of the bed-plate G, 20 when, owing to the construction of the parts, the clutch mechanisms are simultaneously released and the shafts C' and D' thereby stopped. The shafts B and C are then put in motion by means of the toothed portions 25 of the mutilated wheels F' coming in contact with the pinions of the bevel-wheels B' B', so that the bevel-wheels A' A', with their shafts B and C, are operated, thereby rotating the cams N and P, so that the toggle-levers L M and J K are operated. The cam P, being in advance, raises its connecting-levers, so that the clamp E is first raised, binding the plate of metal against the bed G, where it is firmly held for the action of the 35 upper end of the former D against the projecting edge, which latter is bent upward and against the face H of the bed-plate. The further rotation of the shaft B and its cams permits the lowering of the clamp and former, 40 so that the plate of metal is released from the same. The clutch mechanism of the shaft C' now connects the same with the main shaft, so that the said shaft C' is rotated, whereby the feed-roller H' advances 45 the sheet until its front or bent end is beyond the former Q and clamp R and between the rollers J', when, owing to the timing of the clutch mechanism of the shaft D', the latter shaft begins its rotation, so as to operate the rollers J'. 50 When the sheet of metal has been carried by the rollers J' until its rear edge has not quite reached the former Q, and a second sheet which has been fed to the rollers H' has its front end in the position for making the front bend, 55 already described, the shafts C' and D' are simultaneously stopped by the disengagement of the clutches, and the shafts B C are then rotated so that the bends on the rear end of the advanced plate and on the front end of 60 the second plate are made, the bend on the rear end being made by the former Q pressing the edge of the advanced plate into the recessed portion of the bed-plate S. The shaft C' is then rotated so that the rear plate is advanced, being guided on the curved guide Z'

until it passes the bent end of the front plate, when, owing to the bends of the plates being formed in opposite directions, as shown in Figs. 3 and 4, they readily hook or unite. The shaft D' is then rotated so that the 70 plates as united are carried through the device and between the rollers J' when the bends are flattened. A third plate can be united to the second, and the operation as often repeated as desired, thereby forming 75 a continuous sheet of any required length.

Having thus described my invention, what I claim as new, and desire to secure by Letters Patent, is—

1. In an edging-machine for sheet metal, 80 separate formers, toggle-levers connected therewith, rotary shafts with cams operating said levers, a main driving-shaft, mechanism, substantially as described, for separately connecting said rotary shafts with the main 85 driving-shaft, a separate set of rollers for each former, and a guide leading from one former to the other, one set of rollers being on one side of one former and the other set on the opposite side of the other former, 90 said parts being combined substantially as described.

2. In an edging-machine for sheet metal, a frame, two sets of formers and clamps, and feed-rollers on opposite sides having separate 95 operating mechanism, substantially as described, connected by a main driving-shaft, one of said rollers being operated in advance of the operation of the other roller, said parts being combined substantially as described. 100

3. In an edging-machine for sheet metal, a frame with guides, formers and clamps movable in said guides, stationary bed-plates, a main driving-shaft, secondary shafts, and feed-rollers on opposite sides of the machine, with 105 operating mechanism therefor, the mechanism of the feed-rollers on one side operating in advance of the operation of the mechanism of the feed-rollers on the other side, said parts being combined substantially as described. 110

4. In an edging-machine for sheet metal, a frame, two formers moving thereon, and feed-rollers with operating mechanism, substantially as described, for stopping said rollers 115 simultaneously, and operating one in advance of the operation of the other, said parts being combined substantially as described.

5. In an edging-machine for sheet metal, a frame, two separate formers, bed-plates in 120 said frame, operating mechanism for said formers, two sets of rollers, one for feeding the plate of metal to one former and the other for guiding a plate from the other former, a guide leading from one former to 125 the other, and mechanism, substantially as described, for operating one set of said rollers in advance of the other and stopping them simultaneously, said parts being combined substantially as described. 130

6. In an edging-machine for sheet metal, a frame, two separate formers, bed-plates, operating mechanism for said formers, separate sets of rollers for carrying the sheet metal to and from the machine, operating mechanism for said rollers adapted to rotate one set in advance of the other, and a guide for the metal plate leading from one former to the other, said parts being combined substantially as described.
